UNITED STATES PATENT OFFICE.

PERCY C. AVERY, OF CHICAGO, ILLINOIS, ASSIGNOR TO THE SCHUMACHER ACETYLITE LAMP COMPANY, OF SAME PLACE.

DESIGN FOR A LAMP-BODY.

SPECIFICATION forming part of Design No. 30,941, dated June 6, 1899.

Application filed December 29, 1898. Serial No. 700,662. Term of patent 7 years.

To all whom it may concern:

Be it known that I, PERCY C. AVERY, a citizen of the United States, residing at Chicago, in the county of Cook and State of Illinois, have invented and produced a new and original Design for a Lamp-Body, of which the following is a specification, reference being had to the accompanying drawings, which are made a part hereof, and in which—

- o Figure 1 is a side elevation of a lamp-body embodying the new design. Figs. 2 and 3 are respectively a plan and a vertical section thereof.

The subject of the present invention is a design for a lamp-body.

A lamp-body embodying all features of the said design, both essential and minor, is shown in the drawings. It has a chamber A of cylindrical shape in horizontal cross-section, the top a of which is of dome shape, its curvature being continuous, so that when viewed in vertical section it describes a simple curve. Surrounding the tubular portion of this chamber at bottom is an enlarged flange or bead a', which is milled. Rising vertically from the center of the dome is a cylindrical neck B, having a centrally-disposed circumferential groove b. Surmounting this neck is a bell-shaped shell C, the rear portion c of which is rotund. Forward of this rotund portion it has a cylindrical portion c', and forward of this cylindrical portion is a flaring portion c². In each side of the cylindrical portion is a circular opening c³, in which is disposed a light C'. Within the shell is a concavo-convex diaphragm D, having its concave face presented forward. Rising from the top of the shell, opposite the neck B, is a cylindrical short tube

E. In rear of this tube is an opening surrounded by a flange F, surmounted by a milled head F'. Rising from the dome a at the forward side thereof is a curved tube G, which enters an opening C² in the bottom of the shell C, the top of the shell being provided opposite the opening C² with a second opening C³.

The leading essential feature of the design is the chamber A and the superposed bell-shaped shell C, said chamber and shell being substantially of the shapes shown and described.

A minor feature of the design is the neck B, connecting the chamber A and shell C, said chamber and shell being substantially of the shapes shown and described.

Another minor feature of the design is the chamber A, the sides of which are cylindrical in horizontal cross-section, the top of which is of dome shape and the bottom of which is provided with the enlarged flange or bead a', milled substantially as shown and described.

Still another minor feature of the design is the bell-shaped shell C, having the rotund rear portion c, the flaring portion c², and the intervening cylindrical portion c', substantially as shown and described.

Having thus described my invention, what I claim as new, and desire to secure by Letters Patent, is—

The design for a lamp-body substantially as herein shown and described.

PERCY C. AVERY.
